E. SCHUMACHER.

GAS BURNER.

APPLICATION FILED MAR. 16, 1908.

914,193.

Patented Mar. 2, 1909.

A detailed technical illustration of a mechanical assembly. At the top, a vertical rod labeled 'm' is shown with a small circular component. This rod is connected to a larger, more complex structure below. The main structure is a circular base with several holes around its perimeter. Inside this circle, there is a central vertical axis with various mechanical parts attached. The letters 'n' and 'n'' are used to label different parts of the base and the central axis. The drawing uses fine lines and cross-hatching to indicate depth and material texture.

UNITED STATES PATENT OFFICE.

EDWARD SCHUMACHER, OF BUFFALO, NEW YORK.

GAS-BURNER.

No. 914,193.

Specification of Letters Patent. Patented March 2, 1909.

Application filed March 16, 1908. Serial No. 421,516.

To all whom it may concern:

Be it known that I, EDWARD SCHUMACHER, a citizen of the United States, residing at Buffalo, in the county of Erie and State of New York, have invented a new and useful Improvement in Gas-Burners, of which the following is a specification.

This invention relates to an adjustable gas burner which is more particularly designed for use with natural or other gas in steam 10 boilers and annealing furnaces.

The object of this invention is to provide a burner of this character which can be readily adjusted to suit either a high or low pressure 15 of natural gas and also regulated to suit the amount of heat which is required.

In the accompanying drawings: Figure 1 is a longitudinal sectional elevation of my improved gas burner. Fig. 2 is a rear elevation thereof. Figs. 3 and 4 are vertical cross sections of the burner in lines 3—3, and 4—4, Fig. 1, respectively. Fig. 5 is a detached bottom plan view of the rear inner shell section and the parts mounted thereon. 20 Figs. 6 and 7 are fragmentary longitudinal sections on an enlarged scale, of the shutter adjusting devices taken in lines 6—6 and 7—7, Fig. 5.

Similar letters of reference indicate corresponding parts throughout the several views.

In its general organization my improved burner comprises a central forwardly tapering main mixing chamber having front and rear sections A, A¹ which communicate respectively with the furnace and with the external atmosphere, an annular steam chamber B surrounding the rear end of the rear section of the mixing chamber, a rear 35 annular gas chamber C surrounding the central part of the rear section of the mixing chamber, a front annular gas chamber D surrounding the front part of the rear section of the mixing chamber, an annular distributing by-pass E surrounding the rear end of the front section of the mixing chamber and an annular row of auxiliary mixing chambers F arranged around the front part of the front section of the mixing chamber. The 40 rear section of the mixing chamber is formed within an inner forwardly tapering tubular shell a the bore of which is provided with alternating spiral ribs g and grooves g¹ so that the same has the effect of screw 45 threads or rifling, whereby the air, steam or

gas or a mixture of the same is caused to pass forwardly through this section of the mixing chamber with a spiral or whirling motion.

The front section of the mixing chamber is formed in an inner front shell a¹ which 50 abuts at its rear end against the front end of the inner rear shell section and the same is provided with a smooth bore which permits the gaseous fuel to pass freely through the same. Owing to the forwardly tapering 55 formation of the front and rear mixing chamber sections the gaseous mixture is gradually compressed as it passes from the rear to the front end of the same, thereby causing the different gaseous elements in the 60 mixture to be compressed and thoroughly mixed, whereby the mixture upon issuing 65 from the front end of the mixing chamber is in the best condition for perfect combustion and developing the greatest amount of heat. 70

The steam chamber B, rear gas chamber C and front gas chamber D are formed between the outer side or periphery of the inner rear shell section and an outer rear shell section H surrounding the same, this outer rear shell 75 section being preferably formed integrally with the front inner shell section, as shown in Fig. 1. The rear end of the steam chamber is closed by an external annular flange h on the section a bearing with its front side 80 against the rear end of the outer rear shell section and secured thereto by bolts h¹. The steam chamber and the rear gas chamber are separated from each other by an external annular flange or shoulder i arranged on the 85 rear inner shell section a and bearing with its front side against a similar flange or shoulder i¹ in the bore of the outer rear shell. The rear gas chamber and the front gas chamber are separated from each other by an external 90 annular flange or shoulder j on the inner rear shell bearing with its front side against the rear side of an internal flange or shoulder j¹ formed in the bore of the outer rear shell. The distributing by-pass is formed wholly 95 within the connection between the outer rear shell section and the inner front shell section and is separated by a rear wall k from the rear gas chamber while its front side is closed by a front wall k¹. The steam chamber is 100 supplied with steam by means of a pipe L extending through the outer rear shell into said chamber and provided with a valve l whereby the steam is controlled. The steam is 105 delivered from the steam chamber into the mix- 110

ing chamber by means of an annular row of jet openings l^1 extending through the rear inner shell section from the steam chamber into the bottom of the adjacent grooves therein. 5 These jet openings are preferably arranged to form parts of conical volutes so that the steam upon issuing from these openings will be directed into the rear portion of the mixing chamber in spiral lines and thereby join the 10 air entering at the rear of the mixing chamber and moving spirally in the same direction through the mixing chamber, whereby mixing of these elements is promoted.

M represents a gas distributing chamber 15 arranged in the upper portion of the outer rear shell, m a gas supply passage or pipe connected with the distributing chamber, m^1 a branch passage extending from the distributing chamber to the rear gas chamber and N 20 the rotary plug of a valve arranged in the passage m^1 and provided with a port n which may be moved into or out of register with said passage for placing the rear gas chamber in communication with the gas distributing 25 chamber or cutting off communication between the same.

The gas is conducted from the rear gas 30 chamber into the rear section of the mixing chamber by means of an annular row of gas jet openings o extending from the periphery of the inner rear shell section to the bottom of the grooves in the bore thereof which openings are preferably arranged to form parts of conical volutes, so that the gas issuing therefrom will move spirally in the same direction as the air and steam moving through the mixing chamber from the rear end to the front end of the same, thereby aiding in intimately mixing these gaseous elements.

40 The escape of gas through these jet openings o is regulated by means of a ring-shaped shutter o^1 arranged within an annular seat or groove o^2 in the periphery of the inner rear shell section and provided with oblique ports o^3 which are adapted to move into more or less complete register with the oblique outer ends of the rear gas jet openings o and thereby vary the amount of gas which is supplied by these openings accordingly. For the purpose of enabling this ring to be inserted in the groove or seat o^2 the same is split and its opposing ends are provided with ears o^4 which are connected by a bolt or screw o^5 , as shown in Fig. 3. Any suitable means may be provided for turning this annular shutter, the means for this purpose shown in the drawings being suitable and consisting of a longitudinal adjusting spindle or shaft P extending through an opening formed in the flanges h , 55 i of the inner rear section and a web p connecting the same and provided at its front end with a crank pin or offset portion p^1 which engages with a perforated ear p^2 on the shutter o^1 while its rear end is made flat 60 sided to receive a key or handle p^3 for turn-

ing this adjusting shaft. Upon turning this shaft in one direction or the other its crank slides the annular shutter o^1 circumferentially in one direction or the other, thereby varying the effective area of the gas jet openings o and the amount of gas passing through the same accordingly. The rear end of the adjusting shaft P is provided with a pointer q which traverses a scale q^1 on the front end of the inner rear shell section, whereby the 70 position of the annular shutter o^1 may be determined. A stuffing box Q is applied to the adjusting shaft P at the rear end of the opening in the flanges h , i and web p for the purpose of avoiding leakage through this 75 opening.

R represents a branch passage leading from the gas distributing chamber to the front gas chamber, r a gas passage leading from the same to the distributing by-pass E 80 and r^1 the rotary plug of a valve having its port r^2 so constructed that upon turning this plug in one position communication will be established between the gas distributing chamber and the front gas delivery chamber, as shown in Fig. 1, or the front gas chamber 85 may be cut off from the distributing chamber and the latter connected with the distributing by-pass or the distributing chamber may be cut off from the front gas chamber and the 90 distributing by-pass. The gas is conducted from the front gas chamber into the mixing chamber by means of an annular row of jet openings s extending from the periphery of the inner rear shell section within the front gas 95 chamber to the bottom of the spiral grooves in the bore of the inner rear shell section, said jet openings being arranged to form parts of conical volutes so that the gas issuing 100 from the openings s will join the air or mixture flowing through the same and mix properly therewith.

105 The flow of gas through the jet openings s is regulated by means of an annular shutter s^1 seated in an annular groove s^2 in the periphery of the inner rear shell section within the front gas chamber and provided with a plurality of oblique ports s^3 which are adapted to move into more or less complete register with the outer ends of the jet openings s upon 110 turning the shutter s^1 circumferentially in one direction or the other. This turning movement of the shutter is effected by means of a longitudinal adjusting shaft or spindle T journaled in openings formed in the flanges h , i , j and in a web s^3 connecting the flanges h , i and provided at its front end with a crank t 115 engaging with a perforated lug t^1 on the shutter s^1 . Stuffing boxes t^2 , t^3 are applied to the flanges h , j around the shaft T for preventing 120 leakage through said openings which receive this shaft. At its front end the shaft T is made flat sided for the reception of a wrench or key for turning the same and this end of this shaft is also provided with a pointer u 125 130

traversing a scale u^1 on the rear end of the inner rear shell section for determining the position of the shutter s^1 .

The auxiliary mixing chambers F are formed between the periphery of the inner front shell section and an outer front shell section or nozzle V surrounding the former. The front part of the outer front shell section tapers forwardly at the same angle as the inner front shell section but its rear end flares at a greater angle, as shown at v in Fig. 1, and is separated by an intervening space from the outer rear shell section. The auxiliary mixing chambers open at their front and rear ends but are separated lengthwise from each other by means of a plurality of internal flanges, ribs or shoulders v^1 arranged in the bore of the outer front shell section engaging with similar ribs or shoulders v^2 formed on the periphery of the inner front shell section, as shown in Fig. 4. The outer and inner front shell sections are held in place relatively to each other by means of lugs v^3 arranged on the exterior of the rear part of the inner front shell section and screws v^4 whereby the outer front shell section is secured to said lugs, as shown in Figs. 1 and 4.

w represents a plurality of pet cocks or valves connected with the distributing by-pass E and each projecting with its outlet nozzle forwardly into the rear end of one of the auxiliary mixing chambers F. In order to prevent the gas issuing from the cocks w from striking against the internal corner between the front and rear parts of the outer front shell section an outwardly dished cavity w^1 is formed on the inner side of the outer front shell section adjacent to the outlet nozzle of each cock w which operates to lead the gas gradually from said cock to the respective auxiliary mixing chambers, thereby preventing noise and interference with the free flow of the gas through said chambers.

The main air supply for the burner enters through the rear end of the main mixing chamber and the air supply at this point is regulated by means of an adjustable closure applied to the rear end of the mixing chamber which closure is preferably constructed as follows:

X, X represent two semi-circular disk sections or shutters normally arranged transversely at the rear end of the main mixing chamber and having their straight edges opposing each other and adapted when arranged in line to form a complete circular disk which practically closes the rear end of the mixing chamber and shut off the air supply to the same. At their inner opposing edges these shutter sections are pivoted on the parallel legs x, x of a loop shaped arm which is secured at its upper end to the rear end of the mixing chamber by means of a thumb screw x^1 . Upon moving the outer or

free ends of the shutter sections rearwardly more or less the rear end of the main mixing chamber is uncovered in the same measure and air is accordingly admitted to said mixing chamber. These shutter sections are held in their adjusted position by means of two links y, y having their opposite outer extremities pivoted to the rear side of the shutter sections while their inner ends are connected by a clamping bolt z. The pivotal connections between the links y, y and their respective shutter sections X, X are sufficiently tight so that the friction between the links and shutters renders these parts practically one piece when the bolt Z is clamped against the links and thereby holds the same against turning on the rods x, x after the shutter sections have been adjusted to the desired position. When the greatest amount of air is required the thumb screw x^1 is loosened and the shutter sections are swung from the position shown in full lines in Fig. 2, to the position shown by dotted lines in the same figure, whereby the rear end of the mixing chamber is completely uncovered.

When the greatest amount of heat is required the valve l is opened for admitting steam to the mixing chamber, the rear gas-valve N and rear shutter o¹ are opened for admitting gas through the rear gas ports, the front shutter s¹ is opened fully and the front valve r¹ is turned so as to cut off the distributing by-pass and admit a full supply of gas to the front gas chamber. In this position of the parts the air entering through the rear end of the mixing chamber, the steam entering through the jet openings l¹, and the gas entering through the two sets of jet openings o, s form a mixture in the main mixing chamber which upon issuing from the front end of the mixing chamber produces a flame of maximum heating capacity.

The amount of gas admitted to the main mixing chamber should be governed by the distance from the supply to the front end of the burner in order to give the gas and air opportunity to mix properly before ignition. The rear set of gas jet openings o are therefore made larger than the front set of gas jet openings s, thereby adapting the gas supply of these sets of openings to the distance which the same travels through the mixing chamber before being burned and insuring a thorough mixture of the air with the gas from both sets of openings o, s. When less heat is required the supply of gas may be regulated by turning the shutters o¹, s¹ so as to cut down the amount of gas issuing from the two sets of gas openings o, s and by turning off the steam more or less. The steam valve and the shutters o¹, s¹ may also be adjusted relatively to each other as may be necessary to produce the best results according to the quality or character

of the gas which is being used. At times the steam may be cut off entirely and a combustible mixture produced between the air entering at the rear end of the mixing chamber and the gas entering through both sets of jet openings *o, s*.

The steam in addition to serving as an element of the combustible mixture also produces a pressure on the mixture whereby the 10 same is forced into the furnace. When the steam is cut off the natural draft is relied on to carry the mixture from the burner to the furnace. If desired compressed air may be used and supplied by the pipe *L* in place of 15 steam to produce an artificial draft. To further reduce the heat of the flame the rear valve *N* may be closed so that gas is only supplied to the front mixing chamber through the front set of jet openings *s*. While the 20 steam and gas is being supplied through the openings *l, o, s* the cocks *w* are closed and a secondary supply of air enters the furnace through the branch by-passes *F* and mixes at the front end of the burner with the mixture passing through the mixing chamber. When still less heat is required, the valve *r¹* is turned so as to shut off the supply to the front jet openings *s* and place the distributing by-pass *E* in communication with the 30 gas supply and one or more of the cocks *w* are opened according to the size of flame or amount of heat required. The air for admixture with gas supplied by the cocks *w* enters the rear ends of the auxiliary mixing 35 chambers and at this time the rear air shutters *X, X* are closed so as to prevent the passage of an excess amount of air through the main mixing chamber.

By separating the auxiliary mixing chambers from each other it is possible to maintain a flame at the front end of one or more of these chambers without interfering with each other.

From the foregoing description it will be 45 noted that my improved gas burner is capable of a wide range of adjustment and that it is possible to produce a combustible mixture which is capable of producing a large or a small amount of heat with economy and 50 facility.

I claim as my invention:

1. A gas burner comprising a shell the interior of which forms a mixing chamber and which is provided with an annular row of gas 55 jet openings leading into the bore of said shell, an annular shutter mounted on the periphery of said shell and provided with a plurality of ports which are adapted to register with said jet openings, and means for 60 turning said shutter comprising a shaft journaled on said shell and having a crank operatively connected with said shutter, substantially as set forth.

2. A gas burner comprising a shell the interior of which forms a mixing chamber and

which is provided with an annular row of gas jet openings leading into the bore of said shell, an annular shutter mounted on the periphery of said shell and provided with a plurality of ports which are adapted to register with said jet openings and means for 70 turning said shutter comprising a shaft journaled on said shell and having a crank at its front end which is operatively connected with said shutter and a pointer at its rear end 75 which traverses a scale on said shell, substantially as set forth.

3. A gas burner comprising an inner tubular shell forming a mixing chamber within the same and provided with external flanges 80 or shoulders, an outer shell surrounding the inner shell and provided with flanges or shoulders which are engaged by the flanges or shoulders of the inner shell and form an annular gas chamber between said shells, said 85 inner shell having an annular row of gas jet openings leading from said gas chamber to the mixing chamber, an annular movable shutter surrounding the inner shell within the gas chamber and provided with ports adapted 90 to register with said jet openings, a longitudinal shaft journaled in said flanges of the inner shell and provided at its front end with a crank which is operatively connected with said shutter, and a stuffing box applied to 95 said shaft, substantially as set forth.

4. A gas burner comprising a main mixing chamber, a plurality of auxiliary mixing chambers arranged in an annular row around said main mixing chamber, said main mixing 100 chamber being formed within an inner shell and said auxiliary chambers being formed by means of an outer shell surrounding the inner shell and provided with internal longitudinal flanges engaging with similar flanges on the 105 exterior of the inner shell, substantially as set forth.

5. A gas burner comprising a forwardly tapering main mixing chamber, a plurality of auxiliary mixing chambers arranged lengthwise around said main chamber and having the front parts of their outer walls arranged at the same taper as the main mixing chamber while the rear ends thereof are flared rearwardly, and gas cocks discharging into the 115 rear ends of said auxiliary mixing chambers, substantially as set forth.

6. A gas burner comprising a forwardly tapering main mixing chamber, a plurality of auxiliary mixing chambers arranged lengthwise around said main chamber and having the front parts of their outer walls arranged at the same taper as the main mixing chamber while the rear ends thereof are flared rearwardly, lugs arranged on the main mixing 120 chamber and to which the auxiliary chambers are secured, and gas cocks discharging into the rear ends of said auxiliary mixing 125 chambers, substantially as set forth.

7. A gas burner comprising a main mixing 130

- chamber, an annular gas chamber surrounding the main mixing chamber and connected with the latter by an annular row of gas jet openings, a plurality of auxiliary mixing chambers arranged around the main mixing chamber, a distributing by-pass, cocks connected with said distributing by-pass and adapted to discharge into said auxiliary mixing chambers, a gas supply, and a valve 5 adapted to connect the gas supply either with said annular gas chamber or said distributing by-pass, substantially as set forth.
- 10 8. A gas burner comprising a mixing chamber, and a shutter for controlling the admission of air to said mixing chamber having 15 two sections which are pivoted at their opposing edges and an arm carrying said sections and adjustably connected with said mixing chamber, substantially as set forth.

9. A gas burner comprising a mixing chamber and a shutter for controlling the admission of air to said mixing chamber having two sections which are pivoted at their opposing edges, an arm which carries said sections and which is adjustably connected with 20 said chamber, and means whereby said shutter sections are held at different angles relatively to each other consisting of two links pivotally connected at their outer ends to 25 said shutter sections, and a clamping bolt connecting the inner ends of said sections, 30 substantially as set forth.

Witness my hand this 13th day of March, 1908.
